UNITED STATES PATENT OFFICE.

THOMAS EDWARDS, OF SEBASTOPOL, BALLARAT, VICTORIA, AUSTRALIA.

FURNACE FOR ROASTING ORES.

SPECIFICATION forming part of Letters Patent No. 714,464, dated November 25, 1902.

Application filed September 28, 1901. Serial No. 76,868. (No model.)

To all whom it may concern:

Be it known that I, THOMAS EDWARDS, a subject of the King of Great Britain, and a resident of Sebastopol, Ballarat, State of Victoria, Australia, have invented certain new and useful Improvements in Furnaces for the Roasting of Ores and for other Purposes, of which the following is a specification.

My invention is an improvement upon that form of reverberatory furnace for roasting ores disclosed by me in Letters Patent of the United States, dated April 9, 1895, No. 537,024.

In my present invention I have sought to improve the structure of the furnace, to provide a water-cooled rabble which will resist the destructive action of the heat and gases, to give to the rabbles nearest the fire-box or discharge end of the furnace a more rapid rotation in respect to those at the feed end of the furnace, and generally I have sought to increase the durability of the furnace as well as its efficiency.

In the drawings, Figure 1 is a plan view of a part of the furnace. Fig. 2 is a side view, partly broken away. Fig. 3 is a transverse sectional view of the furnace. Fig. 4 is a detail sectional view of one of the rabbles. Fig. 5 is a cross-sectional view of the foot of the rabble, showing the manner of attaching thereto removable wear blocks or teeth; and Fig. 6 is a side view of the rabble; Fig. 7, a detail view.

From the drawings it will be seen that the furnace is substantially of the same elongated form as that shown in my patent referred to, being pivoted centrally of its length at 1, so that it may be tilted by any suitable mechanism—such, for instance, as that shown in Fig. 2 and consisting of a screw 2, pivotally connected to one end of the structure and operated by a worm 3, so as to raise and lower through a nut 4, fixed to a suitable part of the stationary frame or foundation, and thus tilt the furnace-frame.

The furnace comprises the side girders 5, of angle-iron, having straight upper edges and lower edges inclining upwardly from the pivotal point to the ends. These girders are provided with vertical angle-iron stays 6, placed at suitable intervals to make a strong structure. The girders when the furnace is made of considerable length are formed in sections—

as, for instance, those marked *a b c*, jointed together by bolts at 7. The girders on their inner sides carry angle-iron supports 8, extending longitudinally thereof, and upon these rests the metal bottom 9 of the furnace, which is preferably formed of corrugated material. Upon this corrugated bottom may be placed a bed 10, of infusorial earth or other suitable material, and upon this the bricks forming the hearth are laid. The brickwork is continued up the inner sides of the girders, thus forming the side walls of the furnace-chamber, and the furnace-chamber is completed by the arch 11 and the end walls.

The furnace is provided at one end with the fire-box 12, as in the patent referred to, and adjacent to this is located the discharge 13 for the roasted ores, while at the other end of the furnace is arranged the outlet-flue 14. This flue, it will be seen from Fig. 2, is not in the plane of the longitudinal plane of the furnace, but is elevated in respect thereto, consisting of a bent pipe or shell located at 75 the upper part of the furnace-chamber and opening into the same in a downward direction. By this arrangement of the discharge-flue for the gases and products of combustion I avoid the disadvantage present in other arrangements—*i. e.*, the blowing of a portion of the ore by the strong draft from its proper position in the furnace into the main flue which connects with the discharge-flue. This blowing out of parts of the ore is especially 80 apt to occur when the rotary rabble is in operation, stirring and turning over the ore and in a measure raising it.

My present furnace-chamber, like that shown in my patent referred to, is provided 90 with lateral doors 14' for feeding air or for gaining a sight of the interior, and air-holes 15 are also provided at the fire-box end of the furnace. I employ rabbles in my present invention for stirring the ore and for giving 95 it a traversing movement along the hearth from the feeding to the discharge end. These rabbles 16 in their general arrangement and operation are like those described in said patent, with the exceptions to be now noted. 100 I provide means whereby the rabbles will be protected from the destructive action of the heat and of the gases evolved in the roasting of the ore. For this purpose the foot por-

tions 17 of those rabbles it is desired to protect are made hollow. These hollow foot portions are connected with the stems or shafts 18 of the rabbles, which are also hollow and extend up through the arch of the furnace and are connected with suitable driving mechanism outside the furnace-chamber for giving the rabbles their stirring or rotary movement. Each hollow stem 18 is made in sections, which are flanged at 19 and are secured together by bolts. A pipe 20, flanged at its upper end, is held within the lower stem-section by the flange of the pipe being clamped between the flanges of the stem-sections. This pipe communicates with the interior of the upper stem-section. It has about it an annular space in the lower section for the passage of water, and at its lower end it connects with a pipe 21, which extends horizontally of the foot portion and opens into the same, there being a space about this pipe also for the passage of the water. From a point near the upper end of the lower section a discharge-pipe 22 extends, its mouth being directed toward a discharge-pan 23, extending about the stem and supported in fixed position in the arch of the furnace, from which pan the cooling-water is led away, as will be hereinafter described.

30 In Fig. 2 I show water-supply connections leading to the stems of several of the rabbles, these being nearest the fire-box and of course exposed to the most intense heat.

Any desired number of rabbles may be cooled. The supply-pipe for the water is indicated at 24, extending in a direction longitudinally of the furnace and having branches 25 extending upwardly and discharging into the upper open ends of the stems, suitable valves 26 being provided to regulate the flow. The water after passing through the pipes 20 21 flows through the space about said pipes within the hollow rabble and within the lower section of the stem, thus effectually cooling the same and preventing their destruction by the heat and gases and from the upper ends of the stems. The cooling-water passes through the discharge-pipes into the pans and thence through branch pipes 27 to a main discharge-pipe 28, the discharge end of which, 29, depends into or telescopes with a fixed section 30, which conveys the water to any suitable point. By this arrangement the furnace may be tilted as desired without interfering with the cooling action, and the rabbles may likewise be rotated freely while the cooling-water is acting thereon.

In furnaces where only a low degree of heat is required the water will circulate freely through the hollow of the rabble and the interior pipes can be dispensed with.

For placing the pipe 21 in position the foot of the rabble is provided with an opening 31. This is closed by a plug 32.

65 In order to increase the life of the rabble, I provide the same with removable wearing-blocks 33. For the attachment of these blocks

the foot of the rabble is formed with lateral flanges 34, and the wearing-blocks are provided with fingers or extensions 35, engaging these flanges, by which they are held in place thereon. The wearing-blocks in being placed on or removed from the foot portions are simply moved longitudinally of the flanges. The rabbles are driven by bevel-gears on their stem meshing with similar gears on a line-shaft 35'. 7c

For supporting the driving connections I employ an upper framework supported on the side girders 5. This framework comprises the angle-iron frames 36, extending transversely at intervals above the arch of the furnace, said frames being bolted to the upper angle-irons 37 of the side girders. These transverse frames are of general triangular form, comprising inclined sides 37' and upper and lower cross-pieces 38. These cross-pieces support angle-iron beams 39, which extend longitudinally of the furnace, and to them are bolted the bearings 40 of the rabble spindles or stems. At the apex of these triangular supporting-frames bearings 41 are supported, in which the line-shaft turns. The angle-iron framework surmounting the furnace is further provided with braces 41'. 85 The line-shaft is driven from a pulley 43 on a short transverse shaft 44, having its bearings 45 supported on the angle-iron frame. This shaft carries a bevel-gear 46, meshing with a gear on a shaft 47, which is geared to 90 the line-shaft through the gearing 48. 95

I find it desirable to increase the stirring action as the ore reaches a higher degree of roasting upon its approach to the fire-box end of the hearth, and for this purpose I give a greater speed to the rabbles located nearest the fire-box. For instance, I so proportion the gearing of the rabble at the position A that it makes two revolutions for each revolution of the rabble located at B, while the rabble located at C—i. e., the nearest to the fire-box—is geared up to make four revolutions to one of that of the rabble at B. By this arrangement the ore is progressively subjected to a higher temperature. It is stirred and turned over in the hot air. Thus the sulfates are more quickly reduced to oxids, while at the feeding end it is desirable to have the ore particles remain in one position for a somewhat longer period to be acted on by the heat. 105 110 115 120

The stems of the rabbles pass through iron frames 49 into the furnace, said frames being arranged in the arch or roof of the furnace.

The side girders, it will be noticed, are formed of vertical plates having angle-irons riveted thereto at their upper and lower edges. 125

The ore may be supplied to the machine in any suitable manner—for instance, through an opening at Y.

I claim as my invention—

1. In combination in an ore-roasting furnace, a rabble having a hollow stem and foot, said stem being formed in sections, a water-

conducting pipe held in place within the lower section by being clamped between the two sections, a discharge-pipe leading from the lower section and an inlet-pipe leading to the upper section, substantially as described.

5. In combination with a tilting ore-roasting furnace, a hollow rabble therein having a hollow stem, means for rotating the hollow stem and rabble and a water supply and discharge pipe connected with the hollow stem, said water supply and discharge pipe being arranged to permit the furnace to be tilted, substantially as described.

10. In combination with an ore-roasting furnace, a plurality of rabbles with means for driving them simultaneously at different speeds, substantially as described.

15. In combination with an ore-roasting furnace having a fire-box at one end and a discharge at the other end, a plurality of rabbles disposed at different points along the furnace and means for driving the same, the rabbles nearest the fire-box being driven at a greater

speed than those removed therefrom, substantially as described.

20. In combination in an ore-roasting furnace, the sides composed of the angle-iron girders, the brickwork supported by said girders, the rabbles having their stems extending above the furnace, the line-shaft with 30 gearing for operating the rabbles and the transverse triangular-shaped frames of angle-iron, with angle-iron beams connecting them longitudinally, said transverse frames and connecting-beams supporting the bearings for 35 the shafting and the rabble-stems, and said transverse frame being located above the furnace and supported by the angle-iron girders thereof, substantially as described.

25. In testimony whereof I affix my signature 40 in presence of two witnesses.

THOMAS EDWARDS.
